[57] **CLAIM**

The ornamental design for a combined lamp and magnifier lens, as shown and described.

DESCRIPTION

FIG. 1 is a side elevational view of a gooseneck lamp and gooseneck magnifier lens assembly showing my new design with the clamp shown in partially open position;

FIG. 2 is a top elevational view thereof;

FIG. 3 is a bottom view thereof;

FIG. 4 is a front elevational view thereof;

FIG. 5 is a rear elevational view thereof;

FIG. 6 is a side elevational view of another embodiment of the assembly of my new design utilizing a modified clamp and bracket subassembly, with the clamp shown in partially open position;

FIG. 7 is a top elevational view thereof;

FIG. 8 is a bottom view thereof;

FIG. 9 is a front elevational view thereof with the goosenecks shown partially in phantom line and with the cord fragmentarily illustrated; and

FIG. 10 is a rear elevational view thereof.

FIG. 1
